Inventor:

John W. Marden.

UNITED STATES PATENT OFFICE.

JOHN W. MARDEN, OF NORWICH, CONNECTICUT.

CAR-STAKE.

SPECIFICATION forming part of Letters Patent No. 234,681, dated November 23, 1880.

Application filed October 18, 1880. (Model.)

To all whom it may concern:

Be it known that I, JOHN W. MARDEN, of Norwich, in the county of New London and State of Connecticut, have invented a new and 5 useful Improvement in Stakes for Platform-Cars, of which the following is a specification.

The object of my invention is to provide a new and improved car-stake, which is so constructed that it may be dropped down through 10 its socket and be out of the way when the hinged sides of the car are turned down and not in use, and which, when in use, may hold up the said hinged side-board.

The invention consists in a peculiarly-formed 15 socket in which slides a stake, preferably of T-iron, said stake carrying at its top a curved head for holding the side-boards when turned up. When not in use the hinged side-boards drop down, and the stake also drops down with 20 its curved head on a level with the floor of the car. The stakes are further provided with holes and a securing-pin, so that this may be used at any required height without the side-boards.

25 Figure 1 of drawings is a general or plan view of the car with the side-boards in their two positions, and the stakes in the various positions in which they are used. Fig. 2 is the lower socket, through which the stake 30 drops. Fig. 3 is the curved top to hold up side-boards. Fig. 4 is the T-rail, which, in this instance, is used for the body of the stake, and which is the preferable form.

Like letters refer to the same parts in the 35 different figures of the drawings.

A is the socket, to be secured to the edge of the platform or floor of the car. B is the curved top, to be secured to the top of the stake. C is the preferred form of the stake proper. D is 40 the floor of the car. E E are the hinged side-boards in various positions.

a is the slot in the top, to pass over and be secured upon the stake. a' is the slot in the base-socket. c is a square offset or shoulder, 45 upon which the bottom end of the stake may rest when elevated and before the side-boards are turned up. d d are holes in the stake, through which any ordinary pin may be passed to hold it at various heights when the side-boards are not in use and turned down.

50 The socket A is secured in a recess in the edge

of the car-floor, as seen in Fig. 1 of drawings, with the offset or shoulder end downward. After the stake is elevated to its full, or nearly full, length, if its upper end be pulled forward its lower end will then be forced backward and its edge rest upon the lug c. Thus the stakes will all be held up ready for the side-boards. When the side-board is raised and strikes the line of stakes they will all be 60 forced off the shoulder d and drop to the positions shown at the right of Fig. 1.

When the stake is not in use it hangs as seen at extreme left of Fig. 1.

Whenever the side-boards are not required 65 the stakes may be adjusted at any required height and held by pins passing through holes d d.

The top B is secured to the stake by rivets or in any well-known way. The stake may 70 be of wood, and need not, it is evident, be of T shape.

It is evident at a glance that by the use of this sliding stake the same car may be used 75 for coal, gravel, &c, as a simple platform-car for large machinery, when stakes are not needed, and for other merchandise. It is evident, too, that the stakes and side-boards can all be arranged by a single man, as he can set each stake in its socket upon the shoulder 80 or offset, where it will stay until the side-board strikes and automatically lowers an entire row to place.

I am aware of stakes which turn down out 85 of the way upon a pivotal point, and of various arrangements for securing them in these positions.

Having thus described my invention, what I claim as new, and desire to secure by Letters Patent, is—

1. The combination of a sliding stake with a head to drop over and secure a side-board, and a socket secured to the edge of the car, through which the stake drops to a lowered position when not in use, all as and for the 95 purposes set forth.

2. The combination of a sliding stake with its securing head, as set forth, and a lower socket having an offset or shoulder upon which the lower end of the stake may rest to hold it 100 in an elevated position, all as and for the purposes set forth.

3. The combination of a sliding stake with upper end for securing the side-board, a lower socket shouldered to retain the stake when elevated, and perforations upon the stake for holding it at a varied height when side-boards are turned down, all as and for the purposes set forth.

4. The combination of the following elements—viz., a sliding stake, a top for the same embracing arm holding a side-board, a

lower shouldered socket in the edge of a platform-car, through which said stake drops, an adjusting device to hold the stakes at different heights, and hinged side-boards to drop entirely out of the way, all as and for the purposes set forth. 15

JOHN W. MARDEN.
